United States Patent Office

Des. 216,145
Patented Nov. 25, 1969

216,145

CASTER OR THE LIKE

James B. Swett, Barrington, and Harold P. Ashton, Providence, R.I., assignors to Dart Industries Inc., a corporation of Delaware

Filed Aug. 12, 1968, Ser. No. 13,093

Term of patent 14 years

Int. Cl. D7—99

U.S. Cl. D44—7

FIG. 1

FIG. 2

FIG. 3

FIG. 4

FIG. 5

FIG. 6

FIG. 1 is a partially exploded perspective view of a caddy or the like showing our new design;

FIG. 2 is a top plan view;

FIG. 3 is a bottom plan view;

FIG. 4 is a side elevational view;

FIG. 5 is a side elevational view rotated 90° from the position of FIG. 4; and

FIG. 6 is a sectional view on line 6—6 of FIG. 2.

We claim:

The ornamental design for a caddy or the like, substantially as shown.
